UNITED STATES PATENT OFFICE.

ALBERT M. PIGEON, OF NORRISTOWN, PENNSYLVANIA, ASSIGNOR TO WILDMAN MFG. CO., OF NORRISTOWN, PENNSYLVANIA, A CORPORATION OF PENNSYLVANIA.

YARN SEVERING AND CLAMPING DEVICE FOR KNITTING-MACHINES.

1,400,180.

Specification of Letters Patent. Patented Dec. 13, 1921.

Application filed September 21, 1916. Serial No. 121,405.

To all whom it may concern:

Be it known that I, ALBERT M. PIGEON, of Norristown, in the county of Montgomery and State of Pennsylvania, have invented 5 certain new and useful Improvements in Yarn Severing and Clamping Devices for Knitting-Machines, whereof the following is a specification, reference being had to the accompanying drawings.

10 The invention relates more particularly to knitting machines embodying multiple yarn feeds, wherein upon the substitution of one yarn for another it is desired to sever a yarn whose guide is moved to inoperative position. The primary object of the invention is to insure a clean, swift severance of the 15 yarn.

A feature of the invention is the provision of a yarn severing mechanism wherein the 20 movable member of the severing device is spring-actuated and said member is set and tripped by a moving element controlled by a suitable pattern mechanism.

A further feature of the invention is the 25 provision of means whereby the said movable element which serves to set and trip the movable severing member is operated simultaneously with the devices which shift the yarn guides to inoperative position.

30 A still further feature of the invention is to provide an organization of the above character, wherein said severing mechanism is so supported that it may be shifted vertically with the needle cylinder in fashioning and 35 transfer operations and maintain its proper position relative thereto.

In the drawings, which illustrate one embodiment of the invention, Figure I, is a view, partly in longitudinal section and 40 partly in side elevation, of a portion of a knitting machine to which my improvements have been applied.

Fig. II, is a perspective view of the upper portion of the needle cylinder and needles, 45 showing the general relation of the thread feeds and the clamping and severing devices.

Fig. III, is a perspective view of the thread clamping plate, its supporting arm and the operative devices carried thereby.

50 Fig. IV, illustrates in perspective the mov-

able stop arm for the yarn supporting cam plate.

Fig. V, is a detail elevation showing the manner of setting the movable shear blades in readiness to sever a yarn. 55

Fig. VI, is a detail sectional view taken on the line VI, VI, of Fig. I.

Fig. VII, is a detail view showing the operation of the dog during the return stroke of the cam by which the movable member of 60 the shear is actuated.

Fig. VIII, is a detail sectional view on a part of the plane indicated by the line VIII, VIII, in Fig. I.

Fig. IX, is a fragmentary plan view of the 65 yarn supporter cam plate and the adjustable means for preventing its rotation.

The invention comprises primarily a yarn severing device, having a stationary cutting blade and a movable cutting blade. The 70 movable blade is spring-actuated and is controlled by means of a movable trip, which not only raises it to the set position, but releases it at the proper moment, so that the spring may actuate it to sever the yarn. 75 This movable trip is actuated by the same devices which control the position of the yarn guides, so that when a yarn guide is moved to its inoperative position, the cutting blade is set and tripped, and the yarn 80 is severed. Associated with the severing mechanism is a yarn clamping device beneath which the yarn is drawn as it is presented to the severing mechanism, so that the end of the yarn is clamped and held until 85 the yarn guide is returned to effective or operative position, when the yarn will at once be in a position to be fed to the needles. In the machine here shown and described, the cutting and clamping means as a whole is 90 stationary within the circle of needles, and the yarn guide moves up and down outside the circle of needles to carry the yarn into and out of engagement with the needles.

Referring more in detail to the drawings, 95 I have shown my improved yarn severing mechanism as applied to a knitting machine having a needle cylinder 1, mounted for rotation in a supporting ring 2, and driven in any convenient manner from a main driv- 100

ing shaft 3. The knitting is effected through a series of spring beard needles 5, with which beard depressors 6, coöperate. The yarn is supported while being fed to 5 the needles by yarn supporters 7.

Located so as to overhang the needle cylinder is an arm 8, having an angular rear extension 8^a, which is fulcrumed to turn about a rock shaft 9, journaled in fixed 10 brackets 10, extending upwardly from the bed plate 11, of the machine. Clamped to the rock shaft 9, is an arm 12, (see Fig. IV). The arm 12, is provided with a head 13, having a tapered projection 14, adapted 15 to engage within a bifurcation in a fixed stop 15, mounted upon the bed plate of the machine. As shown in Fig. IX, this head 13, projects upwardly and extends between projecting lugs 16, carried by the cap plate 20 17, of the yarn supported dial. These projecting lugs 16, are provided with stop screws 18, which may be adjusted to accurately engage the sides of the head 13, thereby serving as a means for preventing the 25 rotation of the cap plate with the needle cylinder. A sector plate 19, is also fixed upon the shaft 9, and a spring-pressed pin 20, carried by one of the brackets 10, is adapted to engage an opening in the sector 30 plate 19, to prevent rotation of the said shaft, so as to hold the arm 12, in the lowered position shown in Figs. I, and V, of the drawings. The arm may be raised, however, after the pin 20, is withdrawn and 35 said pin may then be dropped into the opening 21, in the sector plate 19, so as to hold the arm in raised position and afford access to the needle cylinder. When the arm 12, is raised, the head 13, is withdrawn from be- 40 tween the arms 16, and this releases the cap plate on the needle cylinder, so that it may be readily shifted about the needle cylinder if desired. The bifurcated stop 15, engag- 45 ing the arm 12, holds the same against lateral movement.

The arm 8^a, is freely mounted on the rock shaft 9, and a spring 22, normally tends to force the outer end 8 of the arm downward. A downward depending stop screw 23, is 50 carried by said arm and is adapted to engage the cap plate 17, and thus limit the downward movement of the arm. The spring 22, is attached at one end to a pin 24, carried by the arm 12, and at the other 55 end to a pin 25, mounted in the portion 8^a of the arm 8. The arm 8, is also provided on its under side with a forwardly projecting web 26, which is provided with an elongated notch 27, to receive the pin 24, there- 60 by allowing a limited independent movement of arm 8, relative to the arm 12. When the arm 8, is raised, however, the pin 24, will be engaged by the lower end wall of the notch 27, and the arm 12, will be raised 65 therewith. This yielding connection be-

tween the arms 9, and 12, permits a compensating range of lost motion of the arm 8, as the needle cylinder is raised and lowered in fashioning or transfer operations, so that all the parts carried by the arm 8, are 70 at all times maintained in accurate operative relation to the needles.

At the forward end of the arm 8, is a transverse extension 28, which supports at its lower end a guard plate 30, see Fig. III. 75 This plate is horizontally disposed within the circle of the needles at a point directly above the top of the needle cylinder. The plate 30, is slotted at 31, to receive and allow for the movement of a downwardly depending shearing blade 32, which coöperates with a substantially horizontal fixed shearing blade 33. This fixed shearing blade is adjustably mounted on the upper surface of the guard plate 30, and has on its upper 80 surface an upstanding pin which helps to guide the yarn. The movable shearing blade 32, is pivotally suspended from the outer end of a link 34, and yieldingly maintained in operative contact with the fixed 85 shearing blade by means of a coiled spring 35. The link 34, is fulcrumed at 36, to the side of the arm 8, and is capable of movement in a vertical plane, within the range limited by the stops 37, and 38, (see Fig. 90 VI). These stops are formed integrally with the lateral extension 28, of the arm 8. The link 34, is moved by means of a link 39, mounted upon the opposite side of the arm 8, and fulcrumed thereon at 40, as 100 shown in dotted lines in Figs. I and V. A clip 41, of inverted L shape is secured to the link 34, by a screw 42, and the horizontal portion of said clip extends over the arm 8, and also over the link 39. A leaf spring 43, 105 bears downwardly against the clip 41, and thereby tends to maintain the link 34, in its lowered position against the lower stop 38. The movements of the link 39, are transmitted through the clip 42, to the link 34. 110 To prepare for the severing action of the movable shearing blade 32, the link 39, is raised by means about to be described, thus lifting the link 34, and blade 32, and placing the spring 43, under tension.

The link 39, is quickly released and the spring 43, throws the movable blade 32, down, severing cleanly the yarn which is laid underneath said blade.

This lifting of the movable blade against 120 the tension of the spring 43, is, in effect, the setting operation of the blade, and when released this spring effects an instantaneous tripping of the blade. This setting and tripping of the blade is brought about by 125 means of the cam sector 45, which is pivotally mounted on the rock shaft 9, and engages a dog 46, pivotally mounted at 47, upon the free rear end of the link 39. The edge or operative face of the cam sector 45, 130

has a portion 48, inclined to the radial line, a curved portion 49, concentric with the axis of rotation and a substantially radial portion 50. In the forward movement of 5 the cam sector (indicated by the arrows in Fig. V), the link 39, is raised by reason of the dog 46, riding up the inclined edge 48. While the curved edge 49 is moving past the dog, the blade is held in its raised position. 10 When the radial edge 50, of the cam sector reaches the dog the latter drops suddenly off the cam edge, thus permitting the link 39, to descend, whereupon the severing mechanism is tripped, allowing the spring 15 43, to actuate the movable shearing blade and cut the yarn.

It will thus be apparent that this cam sector raises the severing blade against the tension of the spring 43, and holds the same 20 in said position for an interval of time, before the tripping occurs. This tripping permits the severing blade to be moved instantaneously and thereby causes a clean cutting of the yarn, which could not be accomplished by a slow movement of the parts, such as ordinarily would result if the moving cutting blade were positively connected 25 with the link actuated by the cam sector.

The return movement of the cam sector 30 45, is ineffective in imparting any further movement to the movable shearing blade, as the dog 46, swings freely about its fulcrum under pressure in that direction, as clearly illustrated in Fig. VII. The dog is formed 35 with a stop 51, which prevents the same from swinging beyond the vertical line when the cam sector is raising the link 39.

Coöperating with the shearing mechanism is a yarn-clamping mechanism, which is 40 constructed as follows: A yarn clamp 52, (see Fig. III), is pivoted upon the pin 44, carried by the link 34, and a spring 53, encircling the pin 44, engages the clamp and presses the same downwardly into contact 45 with the upper face of the fixed shearing blade 33, at a short distance laterally from the slot 31. The upstanding pin on the fixed blade 33 aids in guiding the yarn in proper position in reference to the clamp 52. The 50 lower face of the clamp 52, has a blunt edge, inclined as indicated at 54. The cutting edge of the movable shearing blade is also inclined as indicated, at 55, to facilitate the reception of a yarn when its guide is moved 55 to inactive position.

The cam sector 45, is operated by the link 56, which is pivoted thereto at one end, and at the other end to the operating rod 57, which rotates the controlling drum 58, for 60 the yarn guides. In Fig. II, of the drawings, I have indicated the main yarn guide 59, and supplemental yarn guides 60, 61, and 62, respectively in their inoperative positions. My improved cutting device is 65 adapted to operate upon the yarns carried

by any one of these yarn guides. I have also shown a yarn guide 63, which is in operative position, directing the yarn to the needles. The yarn guides are raised and lowered by the controlling drum 58, in the 70 manner well known in this art.

When the controlling drum is rotated by the rod 57, to operate the yarn guides, the cam sector 45, will be simultaneously oscillated and this in turn will set and trip the 75 movable severing member. When a yarn guide is lifted to inoperative position, the movement of the needle cylinder will carry the yarn (then extending between said yarn guide and the last needle having a loop 80 formed from this yarn), across the plate 30, and underneath the clamp 52, which will clamp the yarn. The yarn will also be drawn between this movable shearing blade and the fixed shearing blade. This operation is so timed as to take place before the 85 movable shearing blade is tripped, so that when said blade is finally released the yarn will be in a proper position to be severed. When this yarn guide is again thrown into 90 action, the movement of the needle cylinder will withdraw the end of the yarn from the yarn clamp.

It is obvious that minor changes in the details of construction and the arrangement 95 of the parts may be made without departing from the spirit of the invention, as set forth in the appended claims.

Having thus described my invention, I claim:

1. A yarn severing mechanism for knitting machines, including in combination, a needle cylinder; needles carried thereby; yarn guides, a relatively fixed shearing blade, a movable shearing blade, a spring 105 for actuating said last named blade for its shearing action; an oscillatory cam; and devices coöperating with said cam to shift and set said movable shearing blade against the tension of the spring, to hold said blade in 110 its set position, and to trip said blade, all during movement of said oscillatory cam one way.

2. A yarn severing mechanism for a knitting machine including a needle cylinder, 115 needles carried thereby, and yarn guides; said mechanism comprising shearing blades movable relatively to one another, and spring actuating means for producing their relative shearing movement; and oscillatory 120 means for shifting and setting said blades against the spring tension and for tripping said blades, said means being ineffective upon the relative positions of said blades during its own movement in one direction.

3. A yarn severing mechanism for knitting machines, including in combination, a needle cylinder; needles carried thereby; yarn guides; a relatively fixed shearing blade; a movable shearing blade; spring 130

means for actuating said last named blade for its shearing action; means for raising the movable shearing blade against the tension of the spring for setting and tripping the same; said means also supporting said severing blades whereby the same are moved up and down with the needle cylinder and maintain the same relative position thereto.

4. A yarn severing mechanism for knitting machines, including in combination, a supporting arm; a fixed shearing blade carried thereby, a movable shearing blade pivotally supported on said arm; a spring for actuating said last named blade for its shearing action; a swinging link for raising said blade, an oscillating sector cam coöoperating with said swinging link for lifting the movable shearing blade and holding the same in set position and for tripping said blade.

5. A yarn severing mechanism for knitting machines, including in combination, a supporting arm; a fixed shearing blade carried thereby; a movable shearing blade pivotally supported on said arm; a spring for actuating said last named blade for its shearing action; a swinging link for raising said movable shearing blade; a pivoted dog carried by the free end of said swinging link; a sector cam having an inclined edge portion adapted to engage said dog for raising the movable shearing blade, a curved concentric edge portion for holding said movable blade in raised position and an abrupt releasing edge portion for tripping said movable blade.

6. A yarn severing mechanism for knitting machines, including in combination, a supporting arm; a fixed shearing blade carried thereby; a movable shearing blade pivotally supported on said arm; a spring for actuating said last named blade for its shearing action; a swinging link for raising said movable shearing blade; a pivoted dog carried by the free end of said swinging link; a sector cam having an inclined edge portion adapted to engage said dog, for raising the movable shearing blade, a curved concentric edge portion for holding said movable blade raised, and an abrupt releasing edge portion tripping said movable severing blade, said dog being pivoted to the swinging link and being provided with a stop for arresting the swinging movement thereof when the sector cam is moving in one direction, while permitting free movement of the dog when the sector cam is moving in the opposite direction.

7. A yarn severing device for knitting machines, including in combination, a needle cylinder; needles carried thereby; a pivoted arm; a spring for yieldingly pressing said pivoted arm toward the needle cylinder; a stop carried by the arm for limiting the movement of the arm toward the needle cylinder; a fixed shearing blade carried by said

arm, a movable shearing blade carried by said arm; a spring for actuating said movable blade for its shearing action; a swinging link for lifting the movable blade; a sector cam adapted to engage said swinging link for raising the movable blade, for holding the same in set position, and for tripping the same.

8. A yarn severing device for knitting machines, including in combination, a needle cylinder provided with a cap-plate; needles carried by said cylinder; a pivoted arm; a spring for yieldingly pressing said pivoted arm toward the needle cylinder; a stop carried by the arm and engaging the cap plate of the needle cylinder for limiting the movement of the arm toward the needle cylinder; a fixed shearing blade carried by said arm; a movable shearing blade carried by said arm, a spring for actuating said last named blade for its shearing action; a swinging link for lifting the movable blade; a sector cam adapted to engage said swinging link for raising the movable blade, for holding the same in raised position, and for tripping the same, and a yarn clamp carried by said arm and adapted to clamp the yarn at a point between the severing edges and the yarn guide.

9. A yarn severing device, for a knitting machine, including in combination, a needle cylinder; needles carried thereby; a pivoted arm; a plate mounted upon the free end of said arm; a fixed severing blade mounted on said plate, said plate having a slot thereon adjacent to the edge of the severing blade; a movable severing blade adapted to coöperate with the fixed severing blade; a swinging link carrying said movable severing blade; a spring engaging said arm and adapted to move the blade for its severing action; a stop carried by the arm for limiting the movement of the blade, a second swinging link engaging the first named swinging link for raising the severing blade, a pivoted dog carried by said second swinging link; and a sector cam adapted to engage said link for raising the severing blade, holding the severing blade in raised position and tripping the same for its severing action.

10. A yarn severing device, for a knitting machine, including in combination, a needle cylinder; needles carried thereby; a pivoted arm; a plate mounted upon the free end of said arm; a fixed severing blade mounted on said plate, said plate having a slot thereon adjacent to the edge of the severing blade; a movable severing blade adapted to coöperate with the fixed severing blade; a swinging link connected to said movable severing blade; a spring engaging said arm for actuating the blade for its severing action; a stop carried by the arm for limiting the movement of the blade; a second swinging link engaging the first named swinging link

for raising the severing blade; a pivoted dog carrier by said second swinging link, a sector cam adapted to engage said dog for raising the severing blade, holding it in raised position, and tripping it for its severing action; a yarn clamp pivotally mounted on the first mentioned swinging link; and a spring normally tending to press said yarn clamp into engagement with the fixed severing blade for clamping the yarn.

11. A yarn severing mechanism for knitting machines including in combination, a needle cylinder, needles carried thereby, yarn guides, a relatively fixed shearing blade, a movable shearing blade, spring means for actuating said movable shearing blade for its shearing action, and oscillatory means for raising and setting the movable shearing blade against the tension of the spring and supporting the same and also tripping the same, all during movement of said oscillatory means one way.

12. A yarn severing mechanism for a knitting machine including a needle cylinder, needles carried thereby, and yarn guides; said mechanism comprising shearing blades stationary within the circle of needles, but movable relatively to one another, with their

cutting edges extending at right angles to the yarn; relatively movable supporting members for said blades extending in substantially the direction of the yarn; and tripping actuating means for said blades.

13. A yarn severing mechanism for a knitting machine including a needle cylinder, needles carried thereby, and yarn guides; said mechanism comprising shearing blades stationary within the circle of needles, but movable relatively to one another; and lying in planes approximately at right angles to one another with their cutting edges extending at right angles to the yarn; relatively movable supporting members for said blades extending in substantially the direction of the yarn; and a clamp member carried by the supporting member of one of said blades and coöperating with the other of said blades to clamp and secure the yarn when severed.

In testimony whereof, I have hereunto signed my name at Philadelphia, Pennsylvania, this twentieth day of September, 1916.

ALBERT M. PIGEON.
